REFRIGERATING APPARATUS

Harry F. Smith, Dayton, Ohio, assignor, by mesne assignments, to General Motors Corporation, a corporation of Delaware

Application November 24, 1930, Serial No. 497,703
Renewed November 13, 1935

27 Claims. (Cl. 62—126)

This invention relates to refrigerating apparatus and more particularly to cooling units or evaporators for use in refrigerating apparatus. The invention is particularly adapted for use with the absorption type of refrigerating system but may also be used with other types of systems especially those employing an evaporator of the flooded type.

One of the objects of the present invention is to provide an improved evaporator structure and more particularly to provide an improved evaporator structure wherein the liquid refrigerant is caused to pass over an increased refrigerating surface by forces generated within the evaporator.

A further object of this invention is to provide an improved evaporator construction employing a liquid refrigerant reservoir wherein means are provided for lifting the liquid refrigerant to a refrigerating surface above the level of liquid in the reservoir.

A still further object is to provide an evaporator for use in absorption machines, said evaporator being so constructed and arranged that its refrigerating surfaces are at all times contacted by cold liquid refrigerant and wherein means are provided for preventing the transfer of hot refrigerant into contact with the refrigerating surfaces.

Further objects and advantages of the present invention will be apparent from the following description, reference being had to the accompanying drawings, wherein a preferred form of the present invention is clearly shown.

In the drawings:

Fig. 1 is a front view of a cooling unit embodying the invention together with a diagrammatic illustration of the remaining elements in an absorption refrigerating system;

Fig. 2 is a vertical longitudinal sectional view of the evaporator;

Fig. 3 is a sectional view along the line 3—3 of Fig. 2;

Fig. 4 is a sectional view along the line 4—4 of Figs. 2 and 3 with the insulation omitted;

Fig. 5 is a sectional view along the line 5—5 of Fig. 6 of a modified form of applicant's invention; and

Fig. 6 is a sectional view along the lines 6—6 of Fig. 5.

In Fig. 1 for illustrative purposes, there is shown diagrammatically an intermittent absorption refrigerating system including a generator-absorber 158 which is connected by a conduit 160 to a condenser 156, cooled by a coil 162, and con-

nected through conduit 164 to an evaporator E, which is supported within the food storage compartment 168 of a refrigerator cabinet 154. The generator-absorber 158 is both heated and cooled by a volatile fluid such as ethyl chloride confined in a closed circuit which includes a vapor shell 170, which may be filled to the level 172, a vapor condenser 174, cooled by a coil 190 and connected to the vapor shell by a vapor conduit 176—178, and a liquid drain connection 180.

When the generator-absorber 158 is to be heated, a burner 182 is lighted and a valve 184 is closed in a valve chamber 186 connected between the conduit connections 176 and 178. The burner vaporizes sufficient liquid in the vapor shell 170 to force most of the liquid up into the condenser 174 through the conduit 180, reducing the level of liquid to 188. Thereafter liquid is vaporized by the burner 182 and condensed on the generator-absorber 158 to heat the latter. When the generator-absorber is to be cooled, the burner is turned off and the valve 184 is opened. The vapor in the shell 170 then flows up into the condenser 174 and the liquid previously held in the condenser drains into the shell 170, submerging the generator-absorber 158. The hot generator-absorber vaporizes this liquid, the vapor being condensed in the condenser 174 and returning as liquid through the conduit 180.

The control system

Water circulates continuously, passing first through the condenser coil 190, through the connecting conduit 192, the condenser coil 162, and thence through a conduit 152 to a valve casing 242 which opens into a jet or entrainment pump having a suction chamber 194 and a throat 196 through which a jet of water is discharged.

The valve casing 242, contains a throttle valve 244 which is opened by a spring 252 and closed by a lever 246 actuated by a bellows 256 connected to the refrigerant conduit 164 by a conduit 258. The jet pump tends constantly to produce a vacuum in the conduit 198 which is provided with a check valve 199 permitting flow of air in the direction of the jet pump but preventing flow of water in the reverse direction which might occur when the flow of water is too low to produce suction. A bellows 200 is connected to the vacuum conduit 198 and operates the valve 184 by means of a lever 204, which includes forked arms 206 pivoted at 208, and a central arm 210 extending within the casing 186, the central arm being sealed to the casing by a packing bellows 212. The pivots 208 are mounted on a second forked

- lever 214, pivoted at 216, having its forked end surrounding the packing bellows 212 which latter may expand and contract against the force of the spring 220 in accordance with changes of pressure in the casing 186. The expansion of the packing bellows 212 depresses the lever 214 to raise an arm 221 to remove a vacuum breaking valve 224 from a ported seat 226, and contraction of the packing bellows raises the arm 214 to 10 permit the vacuum valve to close.

The supply of gas to the burner 182 is controlled by a valve 230 attached to a bellows 232, the interior of which is connected to the vacuum conduit 198. The vacuum conduit system includes a high temperature safety conduit 236, the end of which is closed by a fusible plug 240 disposed in a well in the vapor shell 170.

Operation of the system

- 20 To start the apparatus, the pilot light 234 is lighted and water turned on in the conduit 192. At this time the generator-absorber is saturated with ammonia and the passages in the evaporator E are filled with liquid ammonia. The 25 pressure within the vapor shell 170 is low, therefore the bellows 212 is collapsed to close the vacuum valve 224. The vacuum established by the flow of water collapses the bellows 200 to close the vapor valve 184 and simultaneously collapses the bellows 232 to supply gas to the burner 182. The generator-absorber 158 is now heated as has been explained.

The generator-absorber 158 preferably, but not necessarily, contains a dry absorbent such as strontium chloride. The strontium chloride is rapidly heated by the ethyl chloride and after reaching a certain temperature the strontium chloride begins to distill ammonia which is condensed at a constant rate in the chamber 156 40 by the cooling water. This maintains a substantially constant pressure in the ammonia circuit. Since the ammonia continuously absorbs its latent heat of evolution from the ethyl chloride within the shell 170, the ethyl chloride tends to 45 remain at a constant pressure but when the evolution of ammonia ceases, the pressure of the ethyl chloride suddenly rises. When the pressure corresponding to the tension to which the spring 220 has been set is attained, the bellows 50 212 has expanded sufficiently to open the vacuum valve 224, permitting the gas valve 230 to close and the vapor valve 184 to be opened. This stops the heating period.

Opening of the valve 184 permits circulation 55 of the ethyl chloride which cools the generator-absorber as has been explained, the ethyl chloride being condensed by the cold water in the coil 190 and its pressure rapidly reduced. Likewise, the sudden immersion of the generator-absorber in cold liquid reduces the pressure of 60 ammonia. At this low pressure, the strontium chloride within the generator-absorber 158 absorbs ammonia and produces refrigeration in a well-known manner in the evaporator E. The 65 latent heat of absorption of ammonia is removed by the ethyl chloride which is continuously vaporized on the shell 170 and condensed in the chamber 174. Refrigeration is carried on at a 70 substantially constant temperature because the bellows 256 positions the water valve 244 in response to the temperature of the evaporator and thus regulates the flow of cooling water to maintain a rate of absorption which is in exact accordance with the refrigerating demand, or

closes the valve to stop the apparatus when no refrigeration is required.

The valve 244, for maintaining a constant temperature within the cabinet, can be adjusted by regulating the tension of the auxiliary spring 260 5 by means of the hand operated cam 262 so as to oppose collapsing of the bellows 256 and thus provide a convenient cold control mechanism for the system.

The vacuum conduit system is provided with 10 a restricted opening 266 which is normally closed by the weight of the check valve 270. The size of the opening and the weight of the valve are so proportioned that the valve will not open until a sufficiently low pressure is produced by the 15 jet pump to collapse the two bellows 200 and 232 and thereafter air will not be admitted fast enough to destroy the vacuum necessary to maintain the two bellows collapsed. This arrangement is for the purpose of admitting a small 20 quantity of air in the jet chamber 194 in order that the air may continuously be removed from the chamber by the jet and thus keep the jet sufficiently agitated to maintain a sealing contact with the throat. 25

As the pressure of ethyl chloride is reduced, the spring 220 gradually collapses the bellows 212. After the absorber is completely saturated with ammonia, heat is no longer given up to the ethyl chloride, consequently the pressure of the ethyl 30 chloride gradually drops. When the pressure reaches a certain low point, the spring 220 has collapsed the bellows 212 sufficiently to close the vacuum valve 224 and a new heating period is started. The cycle described repeats itself automatically. 35

If the generator-absorber should become overheated for any reason, for example due to leakage of ethyl chloride from the vapor circuit, the fusible plug 140 will melt to destroy the vacuum 40 and shut off the burner before a dangerous temperature can be reached. In fact heating of the apparatus depends entirely on the assistance of a vacuum which in turn depends both on predetermined flow of cooling water and an intake 45 condition of the control circuit. Therefore, unless cooling water is actually flowing at a sufficient rate to condense the ammonia the burner cannot be lighted. Furthermore, breakage, leakage or failure of any part of the control circuit will break the vacuum to prevent operation 50 of the apparatus.

Difficulty has been encountered in the use of absorption machines of the intermittent type due to the fact that the level of the liquid refrigerant within the evaporator changes between 55 rather wide limits. For instance at the end of the absorption period or at the beginning of the heating period, there is practically no liquid refrigerant within the evaporator while at the end of the heating period the evaporator is substantially filled with liquid refrigerant. Such a fluctuating level of refrigerant decreases the efficiency of the apparatus since hot gaseous and liquid refrigerant is brought in contact with the 60 refrigerating surfaces during the generating period. 65

To overcome these disadvantages, I so construct my improved evaporator that the refrigerating surfaces thereof are at all times, both 70 during the absorption and generating cycles, in contact with relatively cold liquid refrigerant. This is accomplished in my improved construction by stopping the absorption period and starting the heating or generating cycle while a con- 75

siderable quantity of liquid refrigerant still remains in the evaporator. This is also accomplished by utilizing forces generated within the evaporator itself for forcing the liquid refrigerant onto the refrigerating surfaces, these forces being generated only during the absorption period.

In one embodiment of the evaporator E, shown in Figs. 2, 3 and 4, there is shown the tank member 40 which is positioned between the upper sides of the U-shaped plate-type heat absorption member 41 as is more clearly shown in Fig. 4. This heat absorbing member is formed of two sheets or plates of metal 50 and 51 preferably stainless steel, each having a plurality of impervious cup-shaped depressions and corresponding projections formed therein, the outer plate 51 having depressions of greater depth forming projections which fit into the opposite depressions in the inner plate 50. These depressions extend over the greater portion of the bottom and side surfaces of the heat absorbing member 41, but these depressions are omitted at the corners of the U-shaped member 41, as shown at 48, as well as at the top of the sides indicated at 49.

The inner plate 50, near the top of its sides, has two longitudinal depressions 44 therein, one on either side, and also has a pair of opposite semi-spherical depressions 45 in the center of the long depressions 44. The outer sheet 51 has a bulge 46 on either side opposite the semi-spherical depression 45 on the inner sheet for absorbing the expansion due to welding. The sheets are made first by forming the depressions therein, and putting the sheets together in proper relation which is facilitated by the fact that the projections of the outer sheet fit within the adjacent depressions of the inner sheet. The sheets are then welded together around their edges and at the centers of the inter-engaging projections and depressions and then the assembled sheets are bent upward to form the U-shape of the member. By this form of construction a plurality of connected refrigerant passages 47 are formed between the depressions and projections of the adjacent sheets as well as passages 48 at the lower corners of the U-shaped member and along the passages 49 which form headers at the upper portions of the U-shaped member extending to the front and rear of the unit and which headers communicate with the passages 47. The opposite projections and depressions prevent warping of the sheets during welding.

This type of wall structure has a number of advantages over the older types of wall structure. One of these advantages is the fact that with this structure a much narrower refrigerant space can be obtained and thus a lesser amount of refrigerant is required to fill the refrigerant walls and consequently a lesser amount of refrigerant is required to charge the system.

Another advantage is the fact that in welding no distortion of the sheets will take place. When using sheet materials having a high strength at relatively high temperatures this becomes a very important advantage. This is especially true when stainless steel is used. When welding the nested cup-shaped projections and depressions of applicant's wall to hold the sheets 30 and 31 of applicant's refrigerant wall in spaced relation, the expansion caused by the heat of welding is absorbed by a slight distortion of the cup-shaped projections and for this

reason the wall structure itself is not distorted.

Another advantage of this structure is that the nested construction facilitates the welding operation since it holds the sheets together in proper relation during the welding operation and prevents them from slipping. Upon the completion of the welding operation the nested construction will oppose any forces in the plane of the wall tending to move one sheet with respect to the other.

A shoulder which is formed of a row of projections on the inner sheet 50 is used as a tray support for shelf 52 which supports the upper tray. This tray support shelf is formed of a pair of sheets 53 and 54 each having impervious cup-shaped projections and corresponding depressions formed within. The projections on the lower sheet are longer than the projections on the upper sheet 53 and fit into the depressions formed in the upper sheet 53. The upper sheet 53 is continued beyond the side edges of the lower sheet 54 and is bent upwardly and outwardly on either side, as shown at 55, and fits between the third and fourth row of projections 43 on the inner sheet 50 of the U-shaped member 41. The refrigerant passages 56 are formed about the projections of the sheet 54 between the sheets 53 and 54. The edges of the sheets are welded together to enclose the refrigerant passages. The bottom of the U-shaped member 41 serves as a second tray supporting shelf.

The liquid supply reservoir or tank 40 is positioned above the tray supporting shelf 52 between the two sides of the U-shaped member 41. A duct 57 depends from the rear end of the tank member 40 and extends straight downwardly, passing through the tray support shelf 52 as shown at 58, and then makes a reverse turn 59 which forms a trap portion and finally enters the tray supporting shelf from the bottom as shown at 60. To one side of the duct 57 another duct 63, of a relatively small size, extends upwardly from the tray supporting shelf 52, passes to one side of the tank portion 40, and enters the upper distributing member 64. This duct 63 has its upper end bent, as shown at 65, to direct refrigerant in the direction desired.

This distributing member 64 is made in two parts 66 and 67, the rear portion 66 telescoping within the front portion 67 to facilitate assembly thereof. The duct 68 extends from one side of the distributing member 64 and enters the top portion of the tank member 40. This duct 68 conducts gaseous refrigerant from the distributing member 64 to the tank member 40. The duct 69 extends forwardly from the distributing member 64 and is connected to the duct 70 which passes over the tank member 40 and connects the opposite semi-spherical depressions 45 in the upper portion of the inner sheet 50 of the U-shaped member 41. This duct 69 conducts liquid refrigerant from the distributing member 64 to the U-shaped member 41 through the duct 70 the bulges 45 and the long passages or headers 49 on one side of the unit.

The duct 71 connects into the front end of the tank member 40 and extends rearwardly therefrom alongside of the tank member 40 to the rear of this portion and then is bent downwardly around the tank where it connects to duct 70 shown in Fig. 2 which passes out the rear of the evaporator as shown at 72. This duct forms a connection between the evaporator and the remaining units of the absorption system shown in Fig. 1.

Separating the tank member 40 from the upper ice tray compartment 75 is an L-shaped sheet metal shield 76 which also forms the rear wall of these compartments. This shield 76 has its edges bent up as shown at 77 which are so formed as to rest upon a horizontal row of projections on the inner sheet member 50. At its lower end is flange 78 (Fig. 2) which rests upon the bottom of the U-shaped member 41. The tank member 40 is enclosed at the top by the supporting member 80 which fits between the sides of the U-shaped member and has its edges bent up and turned inwardly as shown at 81 so that it may be secured to the top of the compartment within the refrigerator as shown at 82. This bracket 80 is welded at its outer sides to the top edges of the U-shaped member 41. The tank member 40 is enclosed at its rear and front by sheet metal members 83 and 84. A valve shut-off screw 85 which screws into the front end of the tank member 40 projects directly through this front member 84. Within this enclosure about the tank member 40, granulated cork 86 is placed so that the tank member may be insulated as far as possible from the food storage compartment of the refrigerator as well as the remainder of the evaporator.

A shield 87 is fitted to the front end of the evaporator and is secured thereto by long bolts 88 which are fastened at the rear end to the closure piece 89 which in turn abuts against the rear portion of the shield 76 and the rear end of the U-shaped member 41. These long bolts support a shelf 91 which has its adjacent side curled about one of these long bolts 88 as shown at 90. This shelf at its other side may be supported by stud projecting from the adjacent side wall of the refrigerator and may be used to support milk, cold beverages, and other food products.

In assembling, the tank member 40, the supporting shelf 52, and the rear end 66 of the distributing member 64 and connecting ducts, as heretofore described are assembled independently of the U-shaped member 41 and front portion of the distributing member 64 which are connected by the ducts 69 and 70. In assembling the evaporator E, the assembled tank portion, upper tray shelf 52, and the rear portion 66 of the distributing member 64 together with their connecting ducts are slid as a unit into the assembled U-shaped member 41 and front portion 67 of the distributing member 64 and the only connection required to be made is to weld the joint between the front and rear portions 66 and 67 of distributing member 64. The space between the enclosure and the tank member 40 is then packed with granulated cork. It will thus be seen that a novel and easy method of assembly is provided.

When this evaporator is used with an intermittent absorption type of refrigerating system, the level of the liquid refrigerant in the tank portion of the evaporator fluctuates with the changing cycles. I, however, have constructed this improved evaporator so that liquid refrigerant is kept in contact at all times with the refrigerant surfaces regardless of the fluctuation of the level of liquid refrigerant within the reservoir or tank portion of the evaporator.

In the improved unit, ice trays 91 are placed upon the shelf 52 and the bottom portion of the U-shaped member 41. The liquid within the evaporator seeks its own level and fills the duct 51, the passages in the shelf 52, and the lower portion of the connecting duct 63. Heat absorbed from the ice trays causes the evaporation

of some of the liquid refrigerant in the shelf 52. This evaporated gaseous refrigerant is prevented from returning directly to the tank member 40 by reason of the trap portion 59 in the duct 57. Therefore it must ascend through connecting duct 63 and in doing so bubbles upwardly through this duct and carries liquid refrigerant along with it, similarly to the action of an air lift pump, up to the top bend 65 of the duct 63 where the refrigerant overflows into the distributing member 64. This vapor lift action takes place because the mixed column of vapor and liquid refrigerant is lighter than the solid column of liquid refrigerant of lesser height. The upper end 65 of the duct 63 is bent forwardly so as to direct refrigerant away from the gas duct 68. From this point the gaseous refrigerant separates from the liquid refrigerant and passes back to the tank member 40 through the duct 68. The liquid refrigerant, however, collects in the bottom of the distributing member 64 and flows out therefrom through the duct 69 to the duct 70 and into the passages between the inner and outer sheets 50 and 51 of the heat absorbing member or refrigerating surfaces 41. The distributing member 64 together with the ducts 65 and 68 forms a trap for preventing the flow of liquid refrigerant from the passages between the inner and outer sheets 50 and 51 back to the ice tray shelf 52. The duct 69 acts as an overflowing device for liquid refrigerant within the distributing member. The duct 68, distributing member 64 and pipe 69 serve as a means for conducting evaporated or gaseous refrigerant, from the refrigerated surfaces 41 through headers 49, bulges 45 and conduit 70, back to the refrigerant circulating unit. If the liquid refrigerant within the distributing member should rise above the duct 68, the excess of liquid refrigerant will flow back into the supply reservoir. This vapor lift action carries a sufficient amount of refrigerant to fill the passages within the heat absorbing member 41. It will be seen that this member 41 is thus kept filled with liquid refrigerant and is thus sealed to prevent gaseous refrigerant which might have access thereto through the upper connecting ducts from the tank member 40. It has been found that there is sufficient heat absorbed from various other sources to produce enough boiling to keep the U-shaped absorbing member substantially filled even when the ice trays have not been in use for a considerable length of time. From this it will be seen that an evaporator has been provided whose refrigerating surfaces are at all times in contact with cold liquid refrigerant. Thus during the heating or generating period, hot refrigerant cannot contact these cold surfaces.

In the modification shown in Figs. 5 and 6, there is shown the invention advantageously applied to an evaporator of an ice cream cabinet. Heretofore it has been difficult to secure proper cooling at the top portion of the brine tank in an ice cream cabinet of this type as well as to secure proper circulation of the brine within the tank. Consequently the top of the ice cream within the containers became softer than desired. My principle of invention has been applied to this situation and solves this problem by placing the major portion of the cooling surfaces at the top portion of the brine and above the tank portion of the unit. This also improves circulation of the brine within the brine tank since the cold brine will move to the bottom of the tank to be warmed there and will then rise to the top of

the brine where it will again be cooled by the evaporator.

In my improved construction the cooling unit is inserted into the brine tank 100. Adjacent the 5 large aperture in a wall of the tank a re-enforcing ring member 101 is fitted in the interior of the tank adjacent the aperture and a heavy supporting plate 102 is fit to the outside of the wall of the tank adjacent the aperture. Studs 103 pass 10 through the supporting plate 102, the wall of the brine tank, and the supporting member 101 and fastens these members together. The tank member 104 is fitted within the aperture in the supporting plate 102 and has its rear portion extending 15 rearwardly therefrom inside the brine tank and its front portion extending forwardly outside the brine tank. A shield 105 surrounds the entire portion of the tank member within the brine tank, enclosing an insulating space there- 20 about containing a suitable insulating material such as cork for preventing thermal contact between the brine and the tank member.

The tank member 104 is closed by a rear cap 106. On the lower portion of this cap a large 25 duct 107 extends downwardly through the bottom of the shield 105 into the brine. This duct is closed by a plug 108 at its lower end. A pair of ducts 109 are connected to the duct 107 adjacent its lower end and project upwardly to the heat 30 absorbing portion 110 of the evaporator. Fins 111 are fastened along the lower ends of these connecting ducts 109 for a purpose which is to be later described.

The upper heat absorbing portion 110 has a 35 pair of refrigerant ducts 112 having a cross-section somewhat similar to a key hole. These ducts are connected at the front end by a cross duct 113 and are provided with fins 114 which increase the area of heat transfer between these ducts and 40 brine in the top portion of the tank. A duct 117 returns gaseous refrigerant from the refrigerant ducts 112 to the tank member 104.

Refrigerant is supplied to the tank member 104 through the connection 115 and the conduit 116, 45 which extends upwardly into a dome similar to a steam dome of a steam boiler in the top portion of the tank member 104. The refrigerant fills the major portion of the tank member during the heating period of the cycle and a smaller 50 portion during the cooling portion of the cycle. Refrigerant flows downwardly through the duct 107 and then divides and turns upwardly into the ducts 109 from which the refrigerant absorbs a considerable amount of heat from the brine tank. 55 The absorption of heat causes some of the liquid refrigerant to be evaporated and this of course has a strong tendency to move up the ducts 109. The warm liquid refrigerant also has a tendency to move upwardly, and this is carried along upward- 60 ly with the bubbles of the evaporated refrigerant to the upper heat absorbing member 110 much in the same manner as an air lift operates. Liquid refrigerant in the lower portion of the ducts 112 evaporates, collects in the top portion of these 65 ducts and is removed to the tank member 104 through the duct 117.

Thus there is shown how I am able to supply liquid refrigerant to the heat absorbing member at the top portion of the brine tank and above the 70 tank portion of the evaporator. It will be seen that the invention is not merely limited to an evaporator for the absorption type of refrigerating system but is also adapted to the flooded type of evaporator as well as other types. All that is necessary is to supply a float member, needle

valve, and inlet and outlet ports to the tank member to convert the evaporator shown to the flooded type of evaporator often used with the condenser-compressor-expander type of refrigerating system. The liquid in this flooded type circulates in a similar manner as that described with the absorption type of apparatus. 5

While the form of embodiment of the invention as herein described, constitutes a preferred form, it is to be understood that other forms 10 might be adopted, all coming within the scope of the claims which follow.

What is claimed is as follows:

1. A cooling unit including a U-shaped plate-type refrigerating surface, an ice tray shelf positioned between the sides of the refrigerating surface for supporting an ice tray, the yoke of the U-shaped refrigerating surface being adapted to support a second ice-tray, means for supplying liquid refrigerant to the ice-tray shelf, 15 and means for supplying liquid refrigerant from the ice-tray shelf to the refrigerating surface.

2. An ice tray shelf comprising a generally flat rectangular sheet member having a plurality of impervious depressions and corresponding projections formed therein, a second sheet member having a plurality of impervious depressions and corresponding projections formed therein, said projections of said second sheet member extending into said depressions in said first mentioned sheet member forming a refrigerant space between the sheets surrounding said depressions, said sheet members being bonded together at the bottom portions of said depressions and sealed 30 at the edges to enclose the refrigerant space. 35

3. A cooling unit including a liquid refrigerant supply reservoir, a U-shaped plate type refrigerating surface beneath the supply reservoir, enclosing a freezing chamber, said U-shaped plate type refrigerating surface comprising a pair of 40 sheet metal members each having a plurality of depressions and corresponding projections formed therein, the projections of one sheet extending into the depressions of the other sheet and spacing the portions of the sheets surrounding the 45 depressions and forming a narrow refrigerant space thereby, said sheets being sealed at their edges enclosing the refrigerant space, an ice tray shelf supported between the walls of said U-shaped refrigerating surface within said freezing 50 chamber, and means for supplying said refrigerant space in said U-shaped refrigerating surface with liquid refrigerant from the supply reservoir.

4. A plate type refrigerating element comprising 55 a sheet member having a portion with a plurality of impervious depressions therein, a second sheet member having a portion with a plurality of impervious depressions and corresponding projections formed therein extending into and 60 nesting into the depressions in the first mentioned sheet member, the portions of the sheets surrounding each of the depressions being spaced from each other and forming a refrigerant space between said sheet members, said portions of the 65 sheets surrounding the depressions being sealed together adjacent their perimeters for enclosing the refrigerant space, said sheets also being bonded together at the central portions of the depressions and corresponding projections. 70

5. A plate type refrigerating element comprising 75 a sheet member having a portion with a plurality of impervious depressions and corresponding projections formed therein, a second sheet member having a portion with a plurality of im-

- 5 pervious depressions and corresponding projections formed therein, said projections in said second sheet member extending into the depressions of the first mentioned sheet member, said 5 projections in said second sheet member having a greater height than the depth of the depressions in said first mentioned sheet member for providing a refrigerant space between the portions of said sheet members surrounding each of 10 said depressions, the edges of said sheets being sealed for enclosing said refrigerant space, the end portions of the projections of the second sheet contacting the bottom portions of the depressions of the first sheet.
- 15 6. A plate type refrigerating element comprising a sheet member having a portion with a plurality of depressions and corresponding projections formed therein, a second sheet member having a portion with a plurality of depressions and 20 corresponding projections formed therein, said projections in said second sheet member extending into and being formed to fit into the depressions of the first mentioned sheet member, said projections in said second sheet member having a greater height than the depth of the depressions in said first mentioned sheet member for providing a refrigerant space between the portions of said sheet members surrounding each of 25 said depressions, the edges of said sheets being sealed for enclosing said refrigerant space, the central portions of the interengaging projections and depressions being bonded together to hold the sheet members in proper spaced relation.
- 30 7. A plate type refrigerating unit, comprising a sheet member having a plurality of cup-shaped depressions therein, a second sheet member having a plurality of cup-shaped depressions and corresponding projections formed therein, said projections extending into and being formed to fit into the cup-shaped depressions in said first mentioned sheet member, said projections in said second sheet member having a greater height than the depth of the depressions in said first 35 mentioned sheet member for forming a refrigerating space between the sheet members.
- 35 8. A plate refrigerating unit, comprising a sheet member having a plurality of cup-shaped depressions therein, a second sheet member having a plurality of cup-shaped depressions and corresponding projections formed therein, said projections extending into and being formed to fit into the cup-shaped depressions in said first mentioned sheet member, said projections in said second sheet member having a greater height than the depth of the depressions in said first 40 mentioned sheet member for forming a refrigerating space between the sheet members, the interengaging cup-shaped projections and depressions being bonded together to hold the sheet members in spaced relation.
- 45 9. A plate type refrigerating unit, comprising a sheet member having a plurality of cup-shaped depressions therein, a second sheet member having a plurality of cup-shaped depressions and corresponding projections formed therein, said projections extending into and being formed to fit into the cup-shaped depressions in said first mentioned sheet member, said projections in said second sheet member having a greater height than the depth of the depressions in said first 50 mentioned sheet member for forming a refrigerating space between the sheet members, the interengaging cup-shaped projections and depressions being bonded together to form a refrigerant container,

5 10. A plate type refrigerating unit comprising a sheet member having a plurality of cup-shaped depressions and corresponding projections therein, a second sheet member having a plurality of cup-shaped depressions and corresponding projections therein, the projections of said second sheet member extending into the depressions of said first mentioned sheet member, said projections in said second sheet member having a greater height than the depth of the depressions in the first mentioned sheet member spacing the portions of said sheet members surrounding each of said depressions and forming a refrigerant space therebetween.

10 11. A cooling unit comprising generally flat outer sheet metal walls bent partially around a freezing chamber, some of said walls being formed of a plurality of spaced sheets of metal, each of said spaced sheets having a plurality of depressions and corresponding projections formed therein, the projections of one of the sheets extending into and abutting the depressions of the adjacent sheet, spacing the portions of the sheets surrounding the depressions and forming a space therebetween.

15 12. A cooling unit comprising generally flat outer sheet metal walls bent partially around a freezing chamber, some of said walls being formed of a plurality of spaced sheets of metal, each of said spaced sheets having a plurality of depressions and corresponding projections formed therein, the projections of one of the sheets extending into the depressions of the adjacent sheet, spacing the portions of the sheets surrounding the depressions and forming a space therebetween, said sheets being bonded together at the bottoms of their projections.

20 13. A cooling unit comprising generally flat outer sheet metal walls bent partially around a freezing chamber, some of said walls being formed of a plurality of spaced sheets of metal, each of said spaced sheets having a plurality of depressions and corresponding projections formed therein, the projections of one of the sheets extending into the depressions of the adjacent sheet, spacing the portions of the sheets surrounding the depressions and forming a space therebetween and an ice tray shelf supported between said walls within the freezing chamber, said ice tray shelf comprising a plurality of sheets of metal bonded together at their edges, at least one of the sheets being deformed to provide refrigerant passages between the sheets, and duct means connecting the spaces between the sheets of the outer sheet metal walls and the refrigerant passages in the ice tray shelf.

25 14. A cooling unit including a plurality of spaced sheets of metal extending around the bottom and the sides of a freezing chamber and forming a double walled U-shaped structure, each of said spaced sheets having a plurality of depressions and corresponding projections formed therein, the projections of one of the sheets extending into and abutting the depressions of the adjacent sheet, spacing the portions of the sheets surrounding the depressions and forming a refrigerant space therebetween.

30 15. An evaporator comprising a plurality of sheets of metal fastened and sealed together at their edges and having end portions bent up to 70 form a generally U-shaped structure having vertical side walls terminating at the upper ends with sealed edges, said sheets of metal being separated adjacent the upper edges along the top of the vertical walls of the U-shaped struc- 75

ture to form a longitudinal passage on each side, said sheets being also spaced to provide a plurality of refrigerant passages extending between the sheets from one of the longitudinal passages to the other, an ice tray shelf supported between the sides of the U-shaped structure, said shelf including sheet-like portions spaced apart at certain points and secured together at certain other points to form a refrigerant expansion passage therebetween, and means for conducting refrigerant to said expansion passage in said shelf and to the refrigerant passages between the sheets of the U-shaped structure.

16. An evaporator comprising a U-shaped structure having a pair of vertical wall portions connected at their lower ends formed of a plurality of sheets of metal fastened together and sealed at their edges, said vertical wall portions terminating at their upper ends with sealed edges, said sheets being deformed to provide refrigerant passages between the sheets extending from the upper portion of one of the sides of the U-shaped structure down across the bottom portion and up the other side thereof, said sheets being bonded together between the passages, said sheets being also deformed to provide longitudinal passages connecting the ends of the refrigerant passages extending from one side to the other, a cross duct extending from one longitudinal passage directly to the other longitudinal passage, an ice tray shelf supported between the sides of the U-shaped structure, said shelf including sheet-like portions spaced apart at certain points and secured together at certain other points to form a refrigerant expansion passage therebetween, and means for conducting refrigerant to said expansion passage in said shelf and to the refrigerant passages between the sheets of the U-shaped structure.

40 17. An evaporator comprising a U-shaped structure having a pair of vertical wall portions connected at their lower ends and formed of a plurality of sheets of metal fastened together and sealed at their edges, said vertical wall portions terminating at their upper ends with sealed edges, said sheets being deformed to provide refrigerant passages between the sheets extending from the upper portion of one of the sides of the U-shaped structure down across the bottom portion and up the other side thereof, said sheets being bonded together between the passages, said sheets being also deformed to provide longitudinal passages connecting the ends of the refrigerant passages extending from one side to the other, one of said sheets being further deformed to provide oppositely disposed projections extending longitudinally on the inner face of each side of the U-shaped structure, an ice tray shelf supported upon said projections, said shelf including sheet-like portions spaced apart at certain points and secured together at certain other points to form a refrigerant expansion passage therebetween, and means for conducting refrigerant to said expansion passage in said shelf and to the refrigerant passages between the sheets of the U-shaped structure.

18. An evaporator comprising a U-shaped structure having a pair of vertical wall portions connected at their lower ends formed of a plurality of sheets of metal fastened together and sealed at their edges, said vertical wall portions terminating at their upper ends with sealed edges, said sheets being deformed to provide refrigerant passages between the sheets extending from the upper portion of one of the sides

of the U-shaped structure down across the bottom portion and up the other side thereof, said sheets being bonded together between the passages, said sheets being also deformed to provide longitudinal passages connecting the ends of the refrigerant passages extending from one side to the other, an ice tray shelf comprising a plurality of sheets of metal fastened and sealed together at their edges and being deformed to provide refrigerant passages between the sheets, said ice tray shelf being supported between the vertical wall portions of the U-shaped structure, means for conducting liquid refrigerant to the ice tray shelf, means for conducting liquid refrigerant from the ice tray shelf to the passages in the U-shaped structure.

19. An evaporator comprising a U-shaped structure having a pair of vertical wall portions connected at their lower ends formed of a plurality of sheets of metal fastened together and sealed at their edges, said vertical wall portions terminating at their upper ends with sealed edges, said sheets being deformed to provide refrigerant passages between the sheets extending from the upper portion of one of the sides of the U-shaped structure down across the bottom portion and up the other side thereof, said sheets being bonded together between the passages, said sheets being also deformed to provide longitudinal passages connecting the ends of the refrigerant passages extending from one side to the other, an ice tray shelf comprising a plurality of sheets of metal fastened and sealed together at their edges and being deformed to provide refrigerant passages between the sheets, said ice tray shelf being supported between the vertical wall portions of the U-shaped structure, means for conducting liquid refrigerant to the ice tray shelf, means for conducting liquid refrigerant from the ice tray shelf to the passages in the U-shaped structure, and means for conducting vaporized refrigerant from the longitudinal passages at the top of the vertical wall portions.

20. A sheet metal evaporator for refrigerating apparatus comprising, sheet-like portions secured together at certain points and being spaced apart at certain other points to form refrigerant passages therebetween, said sheet-like portions being bent to form at least three walls of a sharp freezing compartment and providing said evaporator with refrigerating surfaces for cooling air adapted to flow thereover, a shelf disposed within said sharp freezing compartment for supporting a receptacle therein, said shelf including sheet-like portions secured together at certain points and being spaced apart at certain other points to form a refrigerant passage therebetween, said sheet-like portions of said shelf being formed separate from and independent of the sheet-like portions of the walls of the freezing compartment, means for supplying refrigerant to the refrigerant passage in said shelf, and means for conducting refrigerant from the shelf to the refrigerant passages in said walls.

21. A sheet metal evaporator for refrigerating apparatus comprising, sheet-like portions secured together at certain points and being spaced apart at certain other points to form refrigerant passages therebetween, said sheet-like portions being bent to form two vertical side walls and a horizontal wall of a sharp freezing compartment and providing said evaporator with refrigerating surfaces for cooling air adapted to flow thereover, a shelf disposed within said sharp freezing compartment for supporting a receptacle there-

in, said shelf including sheet-like portions secured together at certain points and being spaced apart at certain other points to form a refrigerant passage therebetween, said sheet-like portions 5 of said shelf being formed separate from and independent of the sheet-like portions of the walls of the freezing compartment, means for supplying refrigerant to the refrigerant passage in said shelf, and means for conducting refrigerant from 10 the shelf to the refrigerant passages in said walls.

22. A sheet metal evaporator for refrigerating apparatus comprising, sheet-like portions secured together at certain points and being spaced apart at certain other points to form refrigerant 15 passages therebetween, said sheet-like portions being bent to form two vertical side walls and a bottom wall of a sharp freezing compartment and providing said evaporator with refrigerating surfaces for cooling air adapted to flow there- 20 over, a shelf disposed within said sharp freezing compartment for supporting a receptacle therein, said shelf including sheet-like portions secured together at certain points and being spaced apart at certain other points to form a refrigerant pas- 25 sage therebetween, said sheet-like portions of said shelf being formed separate from and independent of the sheet-like portions of the walls of the freezing compartment, means for supplying refrigerant to the refrigerant passage in said shelf, 30 and means for conducting refrigerant from the shelf to the refrigerant passages in said walls.

23. An evaporator for refrigerating apparatus comprising, sheet metal portions cooperating with one another to provide a refrigerant passage 35 therebetween, said cooperating sheet metal portions being arranged to form at least three impervious walls of a sharp freezing chamber and being exposed to air adapted to flow over said evaporator for cooling said air, a refrigerated 40 shelf within said sharp freezing chamber for supporting a receptacle therein and for dividing said chamber into a plurality of compartments, means for conveying refrigerant from a source of supply directly to said shelf, and means for 45 conducting refrigerant from the shelf into direct contact with the air cooling portion of the evaporator.

24. A cooling unit for a refrigerating system including an evaporator comprising a U-shaped 50 refrigerant circulating air cooling portion and a header at each end of the legs of said portion, each of said headers being in communication with one another, means forming a refrigerant conduit and providing a shelf horizontally disposed 55 between the legs of said U-shaped portion, means for admitting refrigerant to said conduit, means providing communication between said conduit and said air cooling portion of said evaporator, and means for withdrawing refrigerant from 60 said evaporator.

25. An evaporator for a refrigerating system comprising, superimposed outer and inner sheet metal portions secured together and arranged to form the side walls and a bottom wall of a 65 freezing chamber, depressions formed in at least one of said sheet metal portions and extending parallel to and being spaced from the ends of said one of said sheet metal portions and also spaced from the front and back edges of said sheet metal

portion, said depressions cooperating with the other of said superimposed sheet metal portions to form headers located at the ends of the sheet metal portions, said headers being opposed due to the form of the evaporator, embossed portions in at least one of said sheet metal portions providing passages extending over the bottom and side walls of the evaporator and communicating with the two opposed headers, means forming a refrigerant conduit and providing a shelf horizontally disposed between the side walls of the freezing chamber and dividing said chamber into a plurality of compartments, means for supplying refrigerant to said conduit, means providing communication between said conduit and the refrigerant passages in the walls of said freezing chamber, and means for withdrawing refrigerant from said evaporator.

26. A sheet metal evaporator comprising an outer one piece shell and an inner one piece shell bent to form a sharp freezing chamber, an embossed portion in one shell consisting of an arcuate depression spaced from an edge of the shells and cooperating with the other shell to form a header, an embossed portion in one shell spaced from a different edge of said shells and consisting of an arcuate depression cooperating with the other shell to form another header, embossed portions in one shell and forming refrigerant passageways leading from the headers and extending over the exposed surface of the shell forming the sharp freezing chamber, said headers being completely confined within the edges of said shells, a substantially continuous weld around the periphery of the shells to completely seal the evaporator with the exception of inlet and outlet connections, means forming a refrigerant conduit and providing a tray supporting shelf horizontally disposed within said freezing chamber and dividing the interior thereof into a plurality of compartments, and connecting means for maintaining a common refrigerant level in both headers.

27. An evaporator for a refrigerating system comprising, superimposed outer and inner sheet metal portions secured together and having their ends spaced apart to form a U-shaped structure defining walls of a sharp freezing chamber, depressions formed in at least one of said sheet metal portions and extending along and being spaced from the ends of said one of said sheet metal portions and also spaced from the front and back edges thereof, said depressions cooperating with the other of said superimposed sheet metal portions to form headers located adjacent the ends of the legs of the U-shaped structure, said headers being opposed due to the U-form of the evaporator structure, embossed portions in at least one of said sheet metal portions providing passages leading from the headers and extending over the legs and their connecting yoke portion of the structure, a conduit extending between and having its ends connected with said headers for maintaining a common refrigerant level in said evaporator, and a pipe communicating with said conduit above the lowermost point of connection of the ends of the conduit with said headers for conveying refrigerant from the evaporator.

HARRY F. SMITH.
